TOOL

Willis T. Fulton, Oakland, Calif.

Application November 2, 1936, Serial No. 108,388

3 Claims. (Cl. 33—42)

The invention relates to a special tool and more especially to a scribing and cutting tool for floor coverings such as linoleum or the like.

The primary object of the invention is the provision of a tool of this character, wherein the same is so constructed that it can be hand operated for the scribing and cutting of floor coverings such as linoleum or the like so as to have such covering snugly and properly fit at the meeting edges thereof with the walls of an enclosure, the tool being of a novel construction to enable convenient handling thereof and the easy scribing and cutting of the material.

Another object of the invention is the provision of a tool of this character, wherein the scribing element or the cutting blade is supported in a unique manner and novel in arrangement for the successful working of the tool.

A further object of the invention is the provision of a tool of this character, which is simple in its construction, thoroughly reliable and efficient in its operation, light in weight yet strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a fragmentary perspective view of the tool constructed in accordance with the invention set to a piece of work.

Figure 2 is an enlarged fragmentary side elevation partly in section of such tool.

Figure 3 is a fragmentary bottom plan view.

Figure 4 is a fragmentary side view partly in section showing the knife blade fitted with the tool.

Similar reference characters indicate corresponding parts throughout the several views in the drawing.

Referring to the drawing in detail, the tool comprises a frame A cast or otherwise formed and constructed from metal of a kind light in weight yet strong and durable. The frame A is provided with an upwardly arched head 10 providing a leg 11 which is disposed at a slight incline and this leg at opposite sides thereof is fitted with elongated rollers 12 journaled in offset portions 13 and 14, respectively, extended laterally from said leg. At the lower end of the leg 11 is journaled a horizontally rotatable friction roller 15 having the beveled upper portion

16 and the straight peripheral guiding edge 17, respectively, the journal for the roller 15 being indicated at 18 and is separably threaded in the lower end of the leg at the longitudinal center thereof.

Depending from the crown 19 of the arched portion 10 is an arm forming a bracket 20 provided with a fork 21 for accommodating therein a stem 22 for a scribing element, in this instance in the nature of a pin 23, which is angularly set within the stem near its lower end by a set screw 24 and the point 25 of such pin is engageable with a piece of material 26 such as linoleum to be laid upon a floor, the scribing area of such material 26 rides upon a rounded knob 27 formed on and directed inwardly from the leg 11 at a point above the friction roller 15 so that the material 26 can be conveniently scribed as is indicated in Figure 1 of the drawing at 28 when the tool is moved when placed in an upright position and superimposed for guiding upon the material to be scribed and cut.

The stem 22 plays through the fork 21 of the bracket 20 and also through an opening or clearance 29 provided in the crown 19 and is fitted with an adjustable collar 30 against which seats a coiled tensioning spring 31 about said stem. This spring 31 also rests against a washer 32 seated upon the fork 21 of the bracket 20. In this manner the stem 22 is held in a position to have the pin 23 confront the knob 27 for the scribing action of the pin.

The frame A rearwardly of the arched portion 10 is provided with a loop handle 33 which at the toe and heel areas thereof has feet 34 for the frame A. The foot 34 next to the arched portion 10 has a center guideway 35 for the end portion of a resilient strap or strap-like spring 36 which is pivotally coupled at 37 to the lower end of the stem 22 and this spring functions to hold the stem in a position for the close contact of the pin 23 with the work. The under face of the spring 36 is dotted with wear buttons 38.

The spring 36 is held in the guideway 35 by a screw-attached clamping plate 39.

In Figure 4 of the drawing there is shown a cutting blade 40 adjustably held in a hanger 41 adapted for separable fitting in the leg 42 in substitute for the leg 11.

The friction roller 15 maintains the tool at a given point from a wall or baseboard and avoids friction in the use of the tool when scribing or cutting the material 26.

The feet 34 function as gliders for the frame A in the handling of the tool.

The spring 36 functions to have the pin 23 of the cutter 40 correctly operate for various thicknesses of material.

What is claimed is:

- 5 1. A tool of the character described comprising a frame having an upwardly arched portion providing a sloping leg, elongated rollers journaled at opposite side edges of said leg, a bracket formed with the arched portion and depending inwardly thereof, a tensioned stem fitting said bracket, a guide roller at the lower end of the leg, a scribing element carried by said stem, a work engaging knob formed with said leg, and spring means acting upon the stem to hold the scribing member in confronting relation to the knob.
- 10 2. A tool of the character described comprising a frame having an upwardly arched portion providing a sloping leg, elongated rollers journaled at opposite side edges of said leg, a bracket formed with the arched portion and depending inwardly thereof, a tensioned stem fitting said bracket, a guide roller at the lower end of the leg, a scribing element carried by said stem, a work engaging knob formed with said leg, and spring means acting upon the stem to hold the scribing member in confronting relation to the knob.
- 15 3. A tool of the character described comprising a frame having an upwardly arched portion providing a sloping leg, elongated rollers journaled at opposite side edges of said leg, a bracket formed with the arched portion and depending inwardly thereof, a tensioned stem fitting said bracket, a guide roller at the lower end of the leg, a scribing element carried by said stem, a work engaging knob formed with said leg, and spring means acting upon the stem to hold the scribing member in confronting relation to the knob, a handle extending from the frame next to the arched portion, and feet on the handle extension and constituting gliders.

leg, a scribing element carried by said stem, a work engaging knob formed with said leg, spring means acting upon the stem to hold the scribing member in confronting relation to the knob, a handle extending from the frame next to the arched portion, and feet on the handle extension and constituting gliders.

3. A tool of the character described comprising a frame having an upwardly arched portion providing a sloping leg, elongated rollers journaled at opposite side edges of said leg, a bracket formed with the arched portion and depending inwardly thereof, a tensioned stem fitting said bracket, a guide roller at the lower end of the leg, a scribing element carried by said stem, a work engaging knob formed with said leg, and spring means acting upon the stem to hold the scribing member in confronting relation to the knob, a handle extending from the frame next to the arched portion, feet on the handle extension and constituting gliders, and means for regulating the tension on said stem.

WILLIS T. FULTON.
